SLOTTED GUIDE TIP FOR PIPE CONNECTIONS

Webster Felix, 1 Casa Court, Central Islip, N.Y. 11722

Filed May 6, 1971, Ser. No. 141,091

Term of patent 14 years

Int. Cl. D23—01

U.S. Cl. D23—41

FIG. 1

FIG. 2

FIG. 3

FIG. 1 is a front elevational view of a slotted guide tip for pipe connections showing my new design;

FIG. 2 is a side elevational view thereof the opposite side being the same as the side shown; and

FIG. 3 is a rear elevational view thereof.

I claim:

The ornamental design for a slotted guide tip for pipe connections, substantially as shown and described.
